(57) **CLAIM**

We claim the ornamental design for an auto sampler for liquid chromatograph analyzer, as shown and described.

DESCRIPTION

FIG. 1 is a front, top and right side perspective view of an auto sampler for liquid chromatograph analyzer showing our new design

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines shown are for illustrative purposes only and form no part of the claimed design.
